UNITED STATES PATENT OFFICE.

FRANK J. KIMBALL, OF LOS ANGELES, CALIFORNIA, ASSIGNOR TO FRANK J. KIMBALL COMPANY, OF LOS ANGELES, CALIFORNIA, A CORPORATION OF CALIFORNIA.

OIL-BURNING INTERNAL-COMBUSTION ENGINE.

1,232,692.

Specification of Letters Patent. Patented July 10, 1917.

Application filed June 27, 1914. Serial No. 847,571.

To all whom it may concern:

Be it known that I, FRANK J. KIMBALL, a citizen of the United States, residing at Los Angeles, in the county of Los Angeles and State of California, have invented a new and useful Oil-Burning Internal-Combustion Engine, of which the following is a specification.

This invention relates to internal combustion engines of the type in which a mixture of air and fuel is compressed precedent to combustion, and the main object of the present invention is to provide for admitting air and fuel to the cylinder independently, so as to enable relatively short exposure of the fuel and air mixture to the hot walls of the engine cylinder, thereby permitting relatively high compression, and corresponding high efficiency, without premature ignition.

The invention is particularly applicable in connection with two-cycle engines, and an object of the invention in such connection, is to insure complete, positive scavenging of the combustion cylinder before the fuel is admitted thereto.

Another object of this invention is to provide an internal combustion engine which is adapted to use low grade fuel, such as heavy hydrocarbons without the use of high pressure compressors for injecting the fuel.

The accompanying drawings illustrate an embodiment of my invention, and referring thereto:

Figure 1 is a plan view of the engine, partly broken away.

Fig. 2 is a section on line x^2-x^2 in Fig. 1.

Fig. 3 is a section on line x^3-x^3 in Fig. 1.

Fig. 4 is a partial side elevation, partly broken away, showing the air inlet means.

My invention is applicable to an engine with any number of cylinders, but is herein illustrated as applied to a single-cylinder engine of the two-cycle type. Said engine comprises a crank case 1, in which the engine shaft 2 is journaled, said crank case also supporting the main cylinder 3 and a low pressure cylinder 4, formed as an enlarged extension of the main cylinder. A piston 5 works in cylinder 4 and is provided with a flange 8 working as a piston in the cylinder extension 4. Suitable packing rings 10 and 10' are provided on the respective piston means 5 and 8. Said cylinder extension 4 opens into the crank case

1, so that the piston 5 operates to compress air in the crank case in its outward stroke, said crank case having a spring controlled inlet valve 7, to admit air to the crank case during the inward stroke of the piston. A pipe or duct 11 leads from the crank case to a scavenging inlet port 16 in cylinder 3, said cylinder being also provided with an exhaust port 17, the ports 16 and 17 being opened by the piston substantially at the outer end of its movement so as to allow compressed air from the crank case to blow through the cylinder 4, to effect a preliminary scavenging. Piston 5 is provided with a deflector 18 to direct the scavenging air so as to remove as much as possible of the foul gases from the cylinder.

In the head 13 of cylinder 3 is provided an inlet chamber 14 and an inwardly opening inlet valve 15 is provided controlling communication between said inlet chamber and a firing chamber 19 in said head, which opens into the cylinder 3, said valve 15 being normally held closed by a spring 20, whose tension may be adjusted by means 21. A pipe 22 leads to said chamber 14 from a storage chamber 24, which communicates through a spring controlled valve 25, with the cylinder chamber 9 between the enlarged cylinder extension 4 and the piston 5, so as to receive compressed air from said cylinder chamber when the piston member 8 is moving inwardly in the cylinder extension 4. Said cylinder extension, or low pressure cylinder 4 is provided with a spring controlled inwardly opening inlet valve 26, and a throttle pipe 27 leads to this valve from the outer air, the throttle 28 in said pipe being operated by governor means hereinafter described.

Means are provided for supplying fuel together with sufficient air for carrying the same, directly to the cylinder 3, and independently of the supply of air for scavenging and combustion, passing through the air inlet valve 15. For this purpose a pump 30 is provided having its intake valve 31 connected to a carburetor or fuel and air supply means 32, the outlet valve 33 of said pump being connected to pipe 34 leading to a pop-valve 35, opening inwardly into the firing chamber 19 in the head of cylinder 3. Said valve 35 is normally held closed by a spring 36 whose tension is adjusted by means 37, so that it will only open under a

definite high pressure, say one hundred pounds per square inch. The piston 29 of pump 30 may be operated by an eccentric 40 on a shaft 41 which is driven from the engine shaft 2 through suitable chain gearing 43 or otherwise. This shaft 41 may also serve through gearing 42, to drive the governor 44 which, through connections 45, 46, controls the throttle 28 aforesaid, and also, through connections 48 controls a throttle 49, for the carbureter 32. The pump 30 is of small capacity compared to the cylinders 3 and 4, so that the mixture of air and fuel in pump 30 may be raised therein to a relatively high pressure, sufficient to vaporize the fuel by the heat of compression, without requiring the expenditure of more than a small portion of the work done by the engine. Such small capacity of the pump 30 is rendered possible by the fact that only sufficient air is compressed therein to serve as a carrier and vaporizing medium for the fuel.

A supplementary exhaust port 50 is provided in the cylinder 3, in position to be closed by the piston at an intermediate point on its instroke, say at about half stroke, said port communicating with an exhaust passage 51, provided with a valve 52 normally held closed by a spring 53 and opened by the operation of the engine, during a limited time in each instroke of the piston, for example, by a lever 55 engaging the stem 52' of said valve and connected by a rod 54 to a strap 56 for an eccentric 57, on the shaft 41 aforesaid.

Suitable ignition means is provided, for example, a spark plug 60, in the firing chamber 19, and means connected thereto for producing a spark at the proper moment.

The operation is as follows: Assuming that the main cylinder is at the end of the inward or compression stroke, and has compressed a charge of mixture, this compressed charge is ignited by ignition means 60, and the high pressure due to the combustion of the mixture drives the piston forward, on its outward or expansion stroke, and substantially at the end of this stroke the piston 50 opens the ports 16 and 17, allowing air to blow through the cylinder 3, from the crank case 1, so as to effect a preliminary scavenging of the cylinder. During this expansion stroke, the supplementary exhaust valve 52 is held closed by its spring 53, and by the pressure in the cylinder. The piston member 8, has in the preceding instroke, compressed charge of air in the storage chamber 21, and when the pressure in the main cylinder 3 falls, on opening the exhaust port 17, valve 15 is opened by the pressure of this compressed air from said storage chamber, allowing such compressed air to pass into the cylinder 3. The first portion of such compressed air sweeps

through the cylinder while the port 17 is still open, and at the first portion of the instroke of the piston 5, the valve 52 for the supplementary exhaust port 50 is opened by the engine-operated means above described, and a further portion of the air passes into the cylinder 3 from storage chamber 24 while said valve is open, blowing the remainder of the foul gases out through the exhaust port 50, which thus serves to prolong the period of exhaust. At a suitable point in the stroke of the piston 5, preferably before it closes the supplementary exhaust port 50, and after about half of the charge of compressed air has passed from the storage chamber into the cylinder 3, the pump 30, on its downward or compression stroke, develops sufficient pressure on the mixture of fuel and air pumped thereby, to lift the valve 35 and cause a highly compressed mixture of air and fuel, say about one hundred pounds per square inch, to be injected into the firing chamber 19 of cylinder 3, this mixture entering the said chamber substantially in the state of mixed fuel gas and air by reason of the high temperature thereof due to compression in the pump 30, and this mixture being diluted with the balance of the air entering the cylinder through the inlet valve 15 from the storage chamber 24. As soon as, or shortly after the piston 5, in its inward stroke, closes the supplementary exhaust port 50 the pressure in the cylinder rises to equilibrium with that in the storage chamber 24, and the valve 15 closes, the further movement of the piston then compressing the mixture in the cylinder 3 until the end of the inward or back stroke, the cylinder then containing a compressed charge, ready for a repetition of the cycle. This mixture of fuel and air is sufficiently rich to prevent pre-ignition by the high temperature due to compression, but forms an explosive mixture when diluted with the fresh air in the cylinder.

An important advantage of the above described method of operation wherein the combustible mixture of compressed air and fuel is admitted to the cylinder 3 independently of the compressed air supply for positive scavenging and for supporting combustion, is that it permits of a sharp demarcation between the air and fuel supply and enables me to insure positive scavenging of the cylinder by the compressed air supply and at the same time to insure that no combustible mixture will be wasted by outflow through the exhaust.

Another advantage of this method of operation is that the fuel and air mixture, being admitted only during the latter part of the air admission, is retained in contact with the hot metal walls of the cylinder for a shorter time than when all the fuel and air are admitted together,

thereby enabling compression to a higher pressure without danger of premature ignition, and correspondingly increasing the fuel economy of the engine. This economizing action may be still further increased by so timing the operation of the air and fuel compression pump that compressed mixture of air and fuel will continue to be forced into the cylinder during the actual compression, the pressure from the pump being sufficient to overcome the pressure in the cylinder during the first part of the compression, thereby producing a further compressing effect in the cylinder and a retardation of enrichment of the mixture therein till the last possible moment, so as to still further shorten the time of exposure of the fuel to the hot metal, and permit of high compression without pre-ignition. It will be understood that since only a partial cylinder charge is compressed with this operation, it is necessary, in order to attain high compression, to decrease the clearance in the cylinder, so that the capacity of the cylinder space at full compression, bears the proper relation to the capacity thereof when compression begins. Inasmuch as the full capacity of the cylinder is used for expansion, the ratio of expansion of the burnt gases to the compression of the mixture is extremely high with this method of operation, resulting in correspondingly high efficiency.

By drawing in the fuel together with air from a carburetor, by the pump 30 and compressing the fuel and air mixture to a moderately high pressure and correspondingly high temperature, I am enabled to use as a fuel, a low grade hydrocarbon, for example twenty-eight gravity asphalt base oil, and to force it into the cylinder in condition in which it is effectively taken up and mixed with the combustion supporting air, precedent to or during the compression in the cylinder, so that when fully compressed it is burnt without carbonization or waste. In this manner I utilize a cheap grade of fuel, without the necessity of using high compression compressors such as are generally used with such fuel, for pulverization and injection thereof.

What I claim is:

1. In an internal combustion engine, a combustion cylinder, a piston working therein, means for supplying fresh air to the cylinder at the beginning of the compression stroke, a pump of small capacity relatively to said cylinder, means for supplying a mixture of air and liquid fuel to said pump, said pump having its outlet connected to the cylinder adjacent to the fresh air supply means for said cylinder, and said pump being connected for operation by said piston to cause a mixture of liquid fuel and air to be compressed therein to sufficient pressure to vaporize the liquid fuel by the

heat of compression and to force the compressed mixture into the fresh air after it has entered the cylinder, and into the cylinder during compression.

2. In an internal combustion engine, a combustion cylinder, a piston working therein, means for supplying fresh air to the cylinder at the beginning of the compression stroke, a pump of small capacity relatively to said cylinder and developing an excess pressure relatively to said cylinder during part of its compression stroke, means for supplying a mixture of air and liquid fuel to said pump, said pump having its outlet connected to the cylinder adjacent to the fresh air supply means for said cylinder, and said pump being connected for operation by said piston to cause a mixture of liquid fuel and air to be compressed therein to sufficient pressure to vaporize the liquid fuel by the heat of compression and to force the compressed mixture into the fresh air after it has entered the cylinder and into the cylinder during part of its compression stroke.

3. In an internal combustion engine, a cylinder and a piston working therein, said cylinder having an exhaust port opened at the end of the expansion stroke, means for compressing air at low pressure, means for admitting such compressed air to the said cylinder during the compression stroke, and a pump having its outlet connected to the cylinder adjacent the means for admitting air to said cylinder and having its inlet provided with means for supplying a mixture of air and liquid fuel, said pump being of relatively small capacity compared to said cylinder and developing an excess pressure relatively to said cylinder during part of its compression stroke, and being connected for operation by the engine during the compression stroke to compress the mixture of air and liquid fuel to sufficiently high pressure to vaporize the fuel by the heat of compression, and to force such compressed mixture, while still at high temperature, into the air after it has entered said cylinder during the compression stroke, and into the cylinder during the compression stroke, independently of the low pressure compressed air supply to the cylinder.

4. In an internal combustion engine, the combination of a cylinder and a piston working therein, said cylinder being provided with exhaust and preliminary scavenging air inlet ports opened by the piston at the end of its expansion stroke, and with a main air inlet port, means operated by the engine for supplying scavenging air to said preliminary scavenging air inlet port when it is opened by the piston, means for supplying compressed air to the main air inlet port during the compression stroke, and means for supplying fuel adjacent to the main air

inlet port of the cylinder during the compression stroke, independent of the compressed air supply.

5. In an internal combustion engine, a main cylinder, a piston working therein, said cylinder being provided with an exhaust port opened by the piston at the end of the expansion stroke, a low pressure cylinder and a piston working therein and connected to the aforesaid piston to compress air in the low pressure cylinder on the compression stroke of the piston in the main cylinder, a storage means connected to receive the compressed air from said low pressure cylinder, a main air inlet valve for the main cylinder, for admitting compressed air thereto from said storage means during the first part of the compression stroke, supplementary exhaust means for the main cylinder for maintaining an open exhaust therefor during the first part of the compression stroke and for closing such exhaust during the balance of the compression stroke and substantially all of the expansion stroke, and means for compressing a mixture of fuel and air to high pressure and supplying such compressed mixture to the main cylinder during the latter part of the time of supply of compressed air thereto, and independently of such compressed air supply.

6. In an internal combustion engine, the combination with a cylinder and a piston working therein, said cylinder having exhaust and scavenging inlet ports opened by

the movement of the piston at the end of its expansion stroke, of supplementary exhaust valve means operated by the engine to open an exhaust connection during the first part of the compression stroke of the piston, and to close such exhaust connection during the remainder of the compression stroke and substantially all of the expansion stroke, means operated by the engine for compressing scavenging air in the expansion stroke of the piston and blowing it through said scavenging inlet and exhaust ports, at the end of the expansion stroke, a storage chamber, means operated by the engine, in its compression stroke, for compressing air into said storage chamber, a connection including a spring controlled valve, between said storage chamber and said cylinder, to admit compressed air to the cylinder only on a definite excess of pressure of such air over the pressure in the cylinder, and means for supplying a compressed mixture of air and fuel to the cylinder, independently of said compressed air supply, during the latter part of the period of admission of such compressed air.

In testimony whereof I have hereunto set my hand, at Los Angeles, California, this 22nd day of June 1914.

FRANK J. KIMBALL.
